CLAIM

The ornamental design for a replaceable pulley lagging pad, as shown and described.

DESCRIPTION

FIG. 1 is a top right front perspective view of one embodiment of a replaceable pulley lagging pad, showing our new design;

FIG. 2 is a top plan view;

FIG. 3 is a bottom plan view;

FIG. 4 is an elevational view of one end, the opposite end being substantially a mirror image thereof;

FIG. 5 is an elevational view of one lateral edge, the opposite lateral edge being substantially a mirror image thereof;

FIG. 6 is a top perspective view of a second embodiment of our new design, for a replaceable pulley lagging pad illustrating a portion of the tread pattern, it being understood that said pattern is repeated uniformly throughout the length of the pad as shown by solid lines;

FIG. 7 is a transverse sectional view taken on the line 7—7 in FIG. 2.

In FIGS. 2 and 7, the outline of a pulley and pair of retainers engaging the pad flanges is for illustrative purposes only and forms no part of the design.
